EGG SHIPPING CONTAINER

Harry C. Reeser, North Hollywood, Calif., assignor to The Patent and Licensing Corporation, New York, N. Y., a corporation of Massachusetts

Application March 1, 1949, Serial No. 79,015

6 Claims. (Cl. 229—15)

1

This invention relates to shipping containers and is particularly concerned with compartmented containers adapted for the shipment of eggs and made of corrugated or solid fiberboard, boxboard, or similar strong, lightweight foldable sheet material.

Shipping containers for eggs, and similar commodities which require relatively frequent inspection and are highly susceptible to injury by external impact, should not only effectively protect their contents from the hazards of shipment and handling but should be strong enough to sustain compression loading of superposed containers and should be adapted to be easily opened and closed at frequent intervals. Further, it is highly desirable that such containers be capable of being shipped in the form of flat blanks which may be readily and quickly assembled by the prospective user. Egg shipping containers heretofore made of lightweight foldable material and devised in an effort to meet the above criteria have generally had one or more commercial disadvantages. For example, they employ an inordinate amount of material in their construction, are difficult to manufacture or assemble, owing, for example, to the use of a plurality of differently-shaped blanks, or are bulky to ship when empty. Prior attempts to simplify the construction of egg shipping containers have frequently resulted in containers deficient in dimensional stability and load-bearing strength, i. e. they do not provide the desired protection for their contents.

It is an object of the invention to provide an improved compartmented shipping container for eggs and the like.

It is a further object of the invention to provide a container of the character indicated which has greater general efficiency and desirability as compared with known containers.

It is a still further object of the invention to provide a compartmented container of simplified construction having dimensional stability and load-bearing strength.

According to the invention, I provide an egg shipping container comprising a case formed from two identical flat blanks, and a centrally-positioned transverse partition member secured to the side walls of the case and dividing the container into two compartments. The cover elements for the container are integral with the end walls of the case and are provided with locking flaps which hold the covers in place, when closed, by frictional engagement with the central transverse partition.

2

Other objects and features of the invention will be apparent from the following description and from the drawings, in which,

Fig. 1 is a view in perspective of an embodiment of the invention,

Fig. 2 is a vertical section taken along the line 2—2 of Fig. 3,

Fig. 3 is a vertical section taken along the line 3—3 of Fig. 1,

10 Fig. 4 is a horizontal section taken along the line 4—4 of Fig. 3,

Fig. 5 is a plan view of the blank forming the body of my container and showing the manner in which the two identical body blanks are positioned for assembly,

15 Fig. 6 is a plan view of the blank forming the partition member,

Fig. 7 is a perspective view showing the manner of assembly of the body and partition blanks, and

20 Fig. 8 is a perspective view of a portion of the container showing details of its construction.

Referring to the drawings, and particularly to Fig. 5, there is shown a substantially rectangular flat blank, designated generally by the numeral 10, which has been cut and scored to permit fabrication of a container embodying features of the present invention. The blank 10 may be formed from a flat sheet of corrugated fiberboard, solid fiberboard, boxboard or other similar foldable material which is lightweight yet possesses adequate flexibility and strength for the purposes of the invention.

The blank 10 has been scored to define a rectangular bottom panel 11, side wall panels 12 and 13, flexibly connected to opposite sides of panel 11 along score lines 14 and 15, respectively, and an end wall panel 16, flexibly connected to one end of bottom panel 11 along score line 17. An extension of end wall panel 16, defined by a score line 18, provides a cover panel 19. The outer edge of cover panel 19 is formed with a locking flap 20, flexibly connected thereto along score line 21. Extending outwardly from the upper portion of opposite sides of end wall panel 16 are

45 bracing strips 22 and 23, flexibly connected to panel 16 along score lines 24 and 25, respectively. It will be observed that bracing strip 22 is substantially longer than bracing strip 23. Top flaps 27 and 28, adapted to be folded inwardly across the top opening of the assembled case, are flexibly connected along score lines 29 and 30 to the edges of bracing flaps 22 and 23, respectively. Top flaps 27 and 28 are separated from cover panel 19 by cuts 31 and 32, respectively. Reinforcement of the end walls of my container is

provided by end liner panels 35 and 36, which are flexibly connected to the side edges of side wall panels 12 and 13 along score lines 37 and 38, respectively, and are separated from end wall panel 16 by cuts 39 and 40, respectively. The panels 35 and 36 are one-half the width of end wall panel 16 so that their end edges will abut when the container is assembled, as shown in Fig. 7. To facilitate handling of the container a convenient hand hold is formed in the end wall panel 16 by cut 41 which defines a flap 42 flexibly connected to panel 16 along a score line 43. Cut-outs 44 and 45 are provided in end liner panels 35 and 36, respectively, and are positioned in such a way that they will coincide with the hand hold formed by cut 41 when the container is assembled.

It is a feature of my container that the body portion is formed from two identical blanks which are adapted to be joined to form a structure having dimensional stability and load-bearing strength. To permit bottom and side wall portions of the two blanks to be securely joined, bottom panel 11 and side wall panels 12 and 13 are provided with attaching flanges. Flange 46 is flexibly connected along score line 47 to bottom panel 11 and flanges 48 and 49 are flexibly connected along score lines 50 and 51 to the ends of side wall panels 12 and 13 respectively. Cuts 52 and 53 separate flange 46 from flanges 48 and 49, respectively.

My complete container is formed from the two identical body members and a centrally-positioned transverse partition member. Referring to Fig. 6, the partition member is formed from a substantially rectangular flat blank designated generally by the numeral 55. Blank 55 is longitudinally scored to define two partition panels 56, flexibly joined along double parallel score lines 57, and securing strips 58 flexibly joined to opposite sides of panels 56 along score lines 59.

It will be observed that the blanks with which I form my container are substantially rectangular and are free from small tabs and the like which might be torn off in handling and which add to the difficulty of manufacture and assembly. My container may be shipped to the user in the form of flat blanks which may be easily and quickly assembled. Only one form of blank is required for constructing the entire body portion of my container. A second form of blank is required only for the transverse partition. The container when assembled has good dimensional stability and will withstand compression loading of several tiers of superposed containers.

To assemble the container, two of the body blanks are first joined by means of attaching flanges 46, 48 and 49. While the two body blanks are identical, in order to facilitate the description, one will be referred to as blank 10 and the other as blank 10a. As shown in Fig. 5, blanks 10 and 10a are positioned with the attaching flange 48 of blank 10 adjacent attaching flange 49 of blank 10a and the attaching flange 49 of blank 10 adjacent attaching flange 48 of blank 10a. The flanges of blank 10 are then attached to the flanges of blank 10a in such a manner that they will extend inwardly into the assembled container. For example, the flanges 46, 48 and 49 are bent upwardly at right angles and the two sets of flanges attached, as by staples 60. The side wall panels 12 and 13 are then bent upwardly and the end liner panels 35 and 36 are bent inwardly in abutting relationship. Referring to Fig. 8, it will be observed that the at-

taching flanges 48 and 49 straddle the flanges 46. Staples or other securing means should not, therefore, be used along the lower ends of flanges 48 and 49. The end wall panels 15 are then bent upwardly and the bracing strips 27 and 28 bent inwardly so that they overlie the side wall panels 12 and 13, respectively. In bringing end wall panels 15 into position, the flap 41 is bent upwardly against panel 15. The bracing strips 28 extend over a portion of the side wall 13 of the adjoining blank and are secured thereto as by staples 60. Bracing strips 22 abut bracing strips 23 and are secured, as by stapling, to the adjacent side wall panels 12. To assemble the partition, securing strips 58 are bent upwardly at right angles to partition panels 56 which are then bent along score lines 57 into overlapping relationship. The partition is directed into position over attaching flanges 46 and 48 as shown in Fig. 8 and the securing strips 58 are attached, as by staples 60, to the side wall panels 12 and 13. The container is then ready to be loaded. After loading, top flaps 27 and 28 are bent inwardly across the top opening of the case, and cover panels 19 are bent downwardly over top flaps 27 and 28. It will be observed that a narrow slot is formed between partition panels 56 and the inner side edges of top flaps 27 and 28. The locking flaps 20 are directed into this slot between the partition panels and the top flaps. The resultant frictional engagement holds the cover panels 19 securely in place yet permits the container to be readily opened. When the contents are to be inspected or removed, the cover panels 19 may be folded back and then again securely closed. Separate covers, which are commonly employed with conventional egg cases are easily misplaced or damaged in the course of the frequent opening and closing to which egg cases are commonly subjected, and in some instances fall off in the course of shipment. My container avoids this disadvantage.

The combined effect of the assembled attaching flanges, bracing strips and partition member gives my container good dimensional stability and permits it to resist compression forces which would tend to injure the contents. The top of my container also provides a load-bearing surface resistant to compression loading of superposed containers. My container will easily sustain compression loading of several tiers of cases with complete protection of its contents.

It will be apparent that various changes and modifications may be made without departing from the scope of the invention as defined in the appended claims and it is intended that all matter contained in the foregoing description and in the drawings shall be interpreted as illustrative and not in a limiting sense.

60 I claim:

1. A compartmented container for the shipment of eggs and the like, comprising two identical body members joined to form a unitary container body, and a transverse partition dividing 65 said container into two compartments, each of said body members comprising an end wall, a bottom, and sidewalls, and inwardly extending attaching flanges integral with the bottom and side walls of said body members, the flanges of one of 70 said body members being secured to the flanges of the other of said body members.

2. A compartmented container for the shipment of eggs and the like, comprising two identical body members joined to form a unitary container body, and a transverse partition dividing 75

said container into two compartments, each of said body members comprising an end wall, a bottom, and sidewalls, inwardly extending attaching flanges integral with the bottom and side walls of said body members, the flanges of one of said body members being secured to the flanges of the other of said body members, and bracing flaps extending from the sides of said end walls and overlying the adjacent side walls, a portion of one bracing flap from each end wall extending to the side wall of the adjacent body member and being secured thereto.

3. A compartmented container for the shipment of eggs and the like, comprising two identical body members joined to form a unitary container body, a transverse partition dividing said container into two compartments, each of said body members comprising an end wall, a bottom, and side walls, inwardly extending attaching flanges integral with the bottom and side walls of said body members, the flanges of one of said body members being secured to the flanges of the other of said body members, cover members integral with said end walls and bendable inwardly to close said compartments, the end edges of said cover members having integral locking flaps, bracing flaps extending from the sides of said end walls and overlying the adjacent side walls, and top flaps extending inwardly from the top edges of said bracing flaps, said top flaps forming a slot with said transverse partition adapted to receive the locking flaps.

4. A compartmented container for the shipment of eggs and the like, comprising two identical body members joined to form a unitary container body, each of said body members comprising an end wall, a bottom, and side walls and inwardly extending attaching flanges integral with the bottom and side walls of said body members, the flanges of one of said body members being secured to the flanges of the other of said body members, said container further comprising a transverse partition dividing said container into two compartments, said partition being formed

by two integral panels folded to provide a double walled member enclosing said attaching flanges.

5. A compartmented container for the shipment of eggs and the like, comprising a bottom, side walls and end walls forming a unitary container body, a transverse partition disposed centrally of said container body and dividing said body into two compartments, cover members for each compartment integral with said end walls and bendable inwardly to close said compartments, the end edges of said cover members having integral locking flaps, bracing flaps extending from the sides of said end walls and overlying the adjacent side walls, and top flaps extending inwardly from the top edges of said bracing flaps, said top flaps forming a slot with said transverse partition adapted to receive the locking flaps.

6. A compartmented container for the shipment of eggs and the like, comprising two identical body members joined to form a unitary container body, and a transverse partition dividing said container into two compartments, each of said body members comprising an end wall, a bottom and side walls, inwardly extending attaching flanges integral with the bottom and side walls of said body members, the flanges of one of said body members being secured to the flanges of the other of said body members, and cover members integral with said end walls and bendable inwardly to close said compartments.
